UNITED STATES PATENT OFFICE

161,370

CARTON SEALER

Joseph A. Rademacher, Green Bay, Wis.

Application March 16, 1948, Serial No. 145,145

Term of patent 3½ years

(Cl. D55—1)

To all whom it may concern:

Be it known that I, Joseph A. Rademacher, a citizen of the United States, residing at Green Bay, in the county of Brown and State of Wisconsin, have invented a new, original, and ornamental Design for a Carton Sealer, of which the following is a specification, reference being had to the accompanying drawing, forming a part thereof.

In the drawing:

Fig. 1 is a side perspective view of a carton sealer embodying my new design, the other side being substantially similar except that the oval housing is omitted.

Fig. 2 is an end elevational view of the same.

Fig. 3 is a reduced plan view thereof.

I claim:

The ornamental design for a carton sealer, as shown and described.

JOSEPH A. RADEMACHER.
